UNITED STATES PATENT OFFICE.

MORRIS L. FILGER, OF CINCINNATI, OHIO, ASSIGNOR OF ONE-HALF TO JACOB REICHERT, OF CINCINNATI, OHIO.

GARBAGE-RECEIVER.

1,174,136.

Specification of Letters Patent.

Patented Mar. 7, 1916.

Application filed April 7, 1915. Serial No. 19,805.

To all whom it may concern:

Be it known that I, MORRIS L. FILGER, a citizen of the United States, and a resident of the city of Cincinnati, in the county of 5 Hamilton and State of Ohio, have invented certain new and useful Improvements in Garbage-receivers, of which the following is a full, clear, and exact description, reference being had to the accompanying drawings, forming part of this specification.

My invention relates to containers or boxes designed to stand in the kitchen or pantry of dwelling houses or hotels, and to provide airtight closures for such garbage receptacles as are to be placed therein.

It is its object to provide a receiver which has compartments for a plurality of containers, closures therefor and compartments for disinfectant, the whole comprising an 20 airtight box of pleasing appearance. This object I accomplish by that certain construction and arrangement of parts to be hereinafter more specifically pointed out and claimed.

25 In the drawings, Figure 1 is a perspective view of the box. Fig. 2 is a central vertical section thereof. Fig. 3 is a perspective view of one of the receptacles.

The box portion of the device has walls 30 1, 1, and a base 2. It is preferred to have legs 3, 3, formed by extending the sides of the box, and the whole may be constructed of wood or, if desired, of enameled ware, so that a pleasing appearance is presented.

35 Hinged at the edge 6, 6, to the back of the box is the lid 7 for the box. This lid is faced on the inside with strips 8 of wood or metal, as the case may be, to form a flange of proper size to just fit into the box portion, and outside of the flange the lid is 40 provided with a gasket 9 of rubber or other material as may be desired. It is thus clear that when the lid is closed down tight it is guided to a proper seat on the box and is 45 provided with an airtight fit by means of the gaskets.

The compartments are formed by means of removable zinc or galvanized iron containers 10, into which the garbage may be 50 directly thrown or into which may be placed a paper bag to receive the garbage directly, said bag to be removed instead of the containers. If two are used, as shown, cover pieces 4 of segmental shape are glued 55 into the four corners of the box, and double

segmental pieces 5 are glued to the sides of the box. Round holes are thus formed within which the cans are placed, and the cover pieces are located below the edge of the box so as to allow circulation above 60 them.

The pocket for disinfectant is formed by a narrow vertical tube 11 set into the hole 12 in the front cover piece 5. Such deodorant or the like as is desired may be 65 placed in this tube, and a series of ventilating holes 20 are made in the tube, thereby disinfecting the box underneath the cover piece.

Pivoted at 13 in a bracket 14 on the base 70 of the box is a foot treadle 15, of any desired kind. A lid lifting rod 16 is pivotally connected to the inner end of the treadle and extends up through the slot 16^a formed in the rear cover piece 5. This rod has 75 pivotal connection with the bracket 17 on the hinged end of the lid, and by pushing down on the treadle the rod is pushed upwardly, thereby lifting the lid.

A brace piece 18 is mounted at the middle 80 of the box for the support of the central cover piece 5, and a pin 18^a is placed on this brace, and a spring 19 is provided connected at one end to the pin and at the other to the bracket 17 on the lid.

85 When it is desired to place garbage in the box, the foot treadle of the box is depressed, thereby raising the lid. The matter is dropped in and the foot treadle released, whereupon the lid will be pulled back to tightly closed position by the spring 19. Any odors that may escape around the joint of the lid and the box are nullified by the disinfectant in the pocket therefor. The disinfectant will circulate within the 90 box above the compartments formed as described, both above and below the cover piece.

95 It is now believed to be plain that a structure is provided of especial utility for the designed purpose. It is compact, convenient and odorless, and can be placed inside of the kitchen instead of out of doors, as is the case with most garbage receptacles now in use.

100 Having thus described my invention, what I claim as new and desire to secure by Letters Patent, is:—

1. In a garbage box and the like, a series 105 of removable compartments, a hinged lid 110

on the box, a foot treadle for raising the lid, and spring means for closing the lid when the foot treadle is released, and means for mounting a container for disinfectant between the compartments.

2. In a garbage box and the like, a series of removable compartments spaced apart, means for mounting a container for disinfectant between the compartments, a lid on the box, a foot treadle for raising the lid, and a rod for connecting said treadle and lid, and a spring for closing the lid, all located in said inter-compartment spaces.

3. In a garbage box and the like, a series

of removable compartments spaced apart, means for mounting a container for disinfectant between the compartments, a lid on the box, a foot treadle for raising the lid, and a rod for connecting said treadle and lid, and a spring for closing the lid, all located in said inter-compartment spaces, said compartments terminating below the edge of the box.

MORRIS L. FILGER.
